UNITED STATES PATENT OFFICE.

FRANK LANSBERG, OF ST. LOUIS, MISSOURI, ASSIGNOR TO THE LANSBERG BRAKE COMPANY, OF SAME PLACE.

AIR-BRAKE.

SPECIFICATION forming part of Letters Patent No. 445,899, dated February 3, 1891.

Application filed May 5, 1890. Serial No. 350,623. (No model.)

To all whom it may concern:

Be it known that I, FRANK LANSBERG, of the city of St. Louis, in the State of Missouri, have invented a certain new and useful Improvement in Air-Brakes, of which the following is a full, clear, and exact description, reference being had to the accompanying drawings, forming part of this specification.

My invention relates to certain improvements in that class of air-brakes in which the air-pressure is reduced in the train-pipe to a certain amount for a service stop and diminished still lower than necessary for a service stop to make an emergency stop.

My invention consists in features of novelty hereinafter fully described, and pointed out in the claims.

Figure I is a longitudinal section illustrative of my invention and showing the parts in the position they occupy when the brakes are not applied, and Fig. II is a similar view showing the parts in the position they occupy when the brakes are applied for an emergency stop.

Referring to the drawings, 1 represents a portion of the train-pipe, communicating through a port 2 with the main chamber 3.

4 represents the pipe leading to the auxiliary reservoir, and 5 the pipe leading to the brake-cylinder.

6 is a slide-valve chamber leading from the chamber 3 to the pipe 4 of the auxiliary reservoir, and in the chamber 6 is located a slide-valve 7. The chamber 6 is round in cross-section, and the valve being flat on one or both of its sides (it is shown flat on one side in Fig. II) permits the passage of the air from the chamber 3 through the chamber 6.

The valve 7 is provided with a groove 8 at its back to receive the inner end of a plug 9, by which the valve is held from turning in its chamber. The plug 9 is held in an opening of the housing by means of a nut or screw-cap 11, between which and the plug a spring 12 is placed, which serves to keep the face of the valve up snugly against the face of the wall of the chamber 6.

The valve 7 is provided with a port 14, extending from its inner face in an inwardly direction to about its center, from where it

extends in a downwardly direction a short distance, (see Fig. I,) and then in an outwardly direction through the side of the valve. (See Fig. II and dotted line, Fig. I.) In this port there is a seat 15 to receive the upper end of a stem 16, having a shoulder 17 just beneath the valve 7, and below this shoulder the stem has secured to it a piston-valve 18, fitting and working in the chamber 3. The stem 16 is secured to the valve 7 by means of a transverse key 19; but a slight movement of the stem within the valve is permitted by making the opening in the stem through which the key passes larger than the key in a vertical direction, or, of course, the opening through the stem might be the same size as the key and the opening in the valve through which the key passes made larger in a vertical direction than the key.

At the lower end of the chamber 6 is a seat 20, against which bears the conical portion 21 of the upper face of the piston-valve 18. The portion 21 of the valve 18 has a notch or groove 22, and by the portion 21 the valve 18 is prevented from coming quite against the upper end or surface of the chamber 3, leaving a space 23 between the upper face of the valve 18 and the upper end of the chamber 3.

24 represents a small groove or port in the upper portion of the side of the cylinder, through which when the valve 18 is raised, the air-pipe passes from the train-pipe into the chamber 23, and escaping through the notch or groove 22 enters the chamber 6, and passes to the auxiliary reservoir, as shown by the arrows in Fig. I.

The features thus far described are not claimed in this application and are the same as the corresponding parts of an application filed by me on the 26th day of April, 1890, Serial No. 349,642.

25 represents a passage forming a communication between the brake-cylinder pipe 5 and the train-pipe 1, and in this passage 25 is located a check-valve 26, as in the application referred to. In this passage 25 is also a valve 27, having a seat 28. On the stem 29 of the valve 27 is a piston-valve 30, fitting in a chamber 31, the stem extending beneath the piston 30 into a guide-cap 32 and sur-

rounded by a spring 33, which keeps the valve 27 in its closed position in the absence of air, and which also keeps the valve in its closed position where there is an equalization of air-pressure above and beneath the piston 30.

34 represents a valve on the stem 16 of the piston-valve 18 and which works in an opening or chamber 35 beneath the chamber 3.

36 represents an exhaust-port controlled by 10 the valve 34 and forming a communication (when the valve 34 is in its lower position) between the chamber 31 beneath the piston 30 and the atmosphere.

37 represents a cushion to receive the impact of the downward movement of the stem 15 of the valve 18.

The operation is as follows: Supposing the train to be running, the air in the train-pipe will keep the piston-valve 18 in its upper position, when the air will pass through the port or groove 24, through the space 23, through the notch or groove 22, and through the chamber 6, around the valve 7 to the auxiliary reservoir. Now suppose a 25 service stop is to be made, the air is reduced in the train-pipe, say, three pounds to the square inch, and the piston-valve 18 descends closing the port 24 and moving the valve 27 down with it as soon as the lost motion of the 30 opening through which the key 19 passes is taken up. The lost motion just referred to opens the port 14 as the upper end of the stem 16 is removed from its seat 15. As soon as the valve 7 descends far enough for the port 35 14 to come opposite or register with a port 40 leading to the passage 25, the air passes from the auxiliary reservoir to the brake-cylinder through the ports 14 40 and passage 25 and the pipe 5 to the brake-cylinder, thus applying the brakes. To release 40 the brakes the air is admitted to the train-pipe again, and the piston-valve and the valve 7 raised to their normal position, as shown in Fig. I, when the air would exhaust from the 45 brake-cylinder through the passage 25 and port 40, and through a port 41 in the face of the valve 7 and a port 42 in the housing of the valve which communicates with the atmosphere. While the train is running, (brakes off,) and also while a service stop is being 50 made, the valve 27 is held to its seat by the spring 33, there being an equalization of pressure above and beneath the piston-valve 30, the air being allowed to enter the chamber 31 through a small port or passage-way 43, as shown by the arrows in Fig. II. This affords or allows the same pressure of air to exist beneath the piston 30 as exists above the piston, thereby equalizing the pressure on 55 the opposite sides of the piston, as stated, so that the spring 33 has merely to sustain the weight of the piston 30, the valve 27, and the stem 29. The reduction of air in the train-pipe for a service stop, as stated, is not sufficient to allow the piston-valve 18 to descend far enough for the slide-valve 34 to open the 60 exhaust-port 36. Now in case of an emergency stop the air in the train-pipe is reduced more than is necessary for a service stop and the piston-valve 18 drops (of course carrying 70 the valve 7 with it, as before, and also, of course, carrying the valve 34 with it) until the valve 34 registers with the port 36 and permits an escape of air through the port 36 from beneath the piston 30. As soon as this 75 takes place the pressure on the upper side of the piston 30 causes this piston to descend, carrying the valve 27 with it, and thus opening a direct communication between the train-pipe and the brake-cylinder through the passage 25, as shown in Fig. II. It will thus be observed that when the train is running, and also during a service-stop, the air in the train-pipe would close the direct communication between the train-pipe and the brake-cylinder, and that when a greater reduction of air is made in the train-pipe than is necessary for a service stop a direct communication is established between the train-pipe and the brake-cylinder for an emergency stop. 80

It will of course be understood that the term "triple valve" employed in the claims refers to the valves 7 and 18 for governing communication between the train-pipe and auxiliary reservoir, and between the latter and brake-cylinder and between the brake-cylinder and exhaust 42.

I claim as my invention—

1. In a fluid-pressure-brake mechanism having a triple valve controlling the admission of air from the train-pipe to the auxiliary reservoir and governing the admission of air from the auxiliary reservoir to the brake-cylinder and also its excretion therefrom, a second valve controlling direct communication between the train-pipe and the brake-cylinder, and a third valve operated by the triple valve for exhausting the air from one side of said second valve when said triple valve is sufficiently operated, as in emergency stops, and causing said second valve to open communication between the train-pipe and the brake-cylinder by reason of the excess of pressure on its other side, whereby the train-pipe pressure and that of the auxiliary reservoir may both be thrown into the brake-cylinder when the controlling triple valve is sufficiently operated.

2. In an air-brake, the combination, with the train-pipe, brake-cylinder pipe, auxiliary-reservoir pipe, and the triple valve, of a passage leading around the triple valve from the train-pipe to the brake-cylinder pipe, a valve in said passage held to its seat by air-pressure, an exhaust-port for relieving the said air-pressure and allowing said valve to open, and a valve for controlling said exhaust-port adapted to open when the air in the train-pipe is reduced more than is necessary for a service stop, substantially as set forth.

3. In an air-brake, the combination of a train-pipe, a passage 25, forming communication between the train-pipe and the brake-cylinder, a valve in said passage held closed

by air-pressure when the train is running and when a service stop is being made, an exhaust-port for releasing the said air-pressure and allowing said valve to open, a valve 5 controlling said exhaust-port and adapted to open when the pressure in the train-pipe is reduced more than is necessary for a service stop, and the triple valve for controlling communication between the train-pipe and auxiliary reservoir and between said reservoir and brake-cylinder, substantially as set forth.

4. In a fluid-pressure-brake mechanism having a triple valve controlling the admission of air from the train-pipe to the auxiliary reservoir, to the brake-cylinder, and also its ejection therefrom, a valve connected with said triple valve and forming a part thereof, another valve controlled thereby, which governs the supply of air directly from 15 the train-pipe to the brake-cylinder when the triple valve is operated for an emergency stop, and a check-valve for preventing back-pressure upon the brake-cylinder through the

valve mechanism to the train-pipe, whereby the pressure of air in the auxiliary reservoir 25 and the train-pipe may both be thrown into the brake-cylinder and back-pressure prevented, for the purpose described.

5. In an air-brake, the combination, with the train-pipe, brake-cylinder pipe, auxiliary reservoir pipe, and the triple valve, of a passage 25, leading around the triple valve from the train-pipe to the brake-cylinder pipe, a valve in said passage 25, held to its seat by air-pressure, an exhaust-port for relieving 30 the said air-pressure and allowing said valve to open, a valve for controlling said exhaust-port adapted to open when the air in the train-pipe is reduced more than is necessary for a service stop, and a check-valve in said 35 passage 25 for preventing backflow, substantially as set forth.

FRANK LANSBERG.
